HUGH CHRISTIE, OF MORRISANIA, NEW YORK, ASSIGNOR TO W. M. BRASHER AND COMPANY.

Design No. 3,378, dated February 16, 1869.

DESIGN FOR A FLOOR OIL-CLOTH PATTERN.

The Schedule referred to in these Letters Patent and making part of the same

To all whom it may concern:

Be it known that I, HUGH CHRISTIE, of Morrisania, county of Westchester, and State of New York, have invented or produced a new and original Design for a Pattern to be Printed upon Floor Oil-Cloths, in colors similar to those painted on the drawings accompanying this specification, or in other colors substituted in the place of those painted on the drawings herewith; and I do hereby declare that the drawings accompanying this specification do give and convey to any one skilled in the art of manufacturing floor oil-cloth, a thorough description of the nature of my invention, and are sufficient to enable any one skilled in the art of manufacturing floor oil-cloth to use my invention.

What I claim as my invention, and desire to secure by Letters Patent, is—

The configuration of the design hereunto annexed, when made by being wrought upon floor oil-cloth in the form similar to the drawings accompanying this specification.

HUGH CHRISTIE.
